Attorney

UNITED STATES PATENT OFFICE.

HEINRICH P. HEITMANN, OF ABLEMAN, WISCONSIN.

HEATING-STOVE.

SPECIFICATION forming part of Letters Patent No. 333,856, dated January 5, 1886.

Application filed May 14, 1885. Serial No. 165,506. (No model.)

To all whom it may concern:

Be it known that I, HEINRICH P. HEITMANN, a citizen of the United States of America, residing at Ableman, in the county of Sauk 5 and State of Wisconsin, have invented certain new and useful Improvements in Heating-Stoves; and I do hereby declare the following to be a full, clear, and exact description of the invention, such as will enable others skilled in the art to which it appertains to make and use the same, reference being had to the accompanying drawing, and to letters or figures of reference marked thereon, which forms a part of this specification.

15 My invention has for its object the provision of an arrangement of flues in connection with a prime and secondary heating stove, whereby two different rooms may be readily heated.

20 In the accompanying drawing the figure represents a sectional view illustrating the relative arrangement of stoves in connection with the dividing-partition and the chimney.

A designates a central vertical dividing-partition, on one side of which is arranged the prime heater B, preferably in the form of a cook-stove. The chimney receives the products of combustion from the stove B by means of a vertical pipe, D, which may be 25 cut off by means of a damper, a, located therein. On the other side of the partition is located the secondary heater, which is, as illustrated, a vertical heating-drum, E, which is provided at or near its base with a fire-chamber, b, to which access may be had 30 through a suitable door, (represented by dotted lines.) Within the vertical drum E are arranged two chambers or compartments, the presence of which form a tortuous passage, c, within said drum, in order that the heat 35 may have a more extended passage to travel for its proper radiation. The drum E communicates at its top with the chimney C by means of a pipe, F. A horizontal pipe, d, establishes a communication between the upper 40 part of the pipe D and the upper part of

the drum E, and is controlled by means of a damper, e. An inclined pipe, f, establishes communication between the lower part of the pipe D and the lower part of the heating-drum, 50 and is controlled by a damper, g.

The operation of the improvement is as follows: When it is desired to heat the room in which the drum E is located without making a fire in the latter, the dampers a e are operated to close their respective pipes and the damper of the pipes F f operated to open said pipes. The heat from the stove B will then pass from the stove through the pipe f and vertically up through the tortuous passage c, through the pipe F into the chimney, thus effectually heating up the radiating-drum E. By closing the damper g and opening the dampers a and e the heat from the stove B will pass through the pipe d, through the upper portion of the drum E, through the pipe F, to the chimney, this draft of heated air being sufficient to impart enough heat to the drum E to temper or moderately heat the room in which it is located. By closing the dampers e and g and opening the damper a the products of combustion will pass directly into the chimney from the stove B.

I claim—

The combination, with a prime heating-stove, a pipe, D, for the discharge of smoke and products of combustion, of a secondary heater, a pipe, f, connecting the base of the secondary heater with the pipe D, a pipe, d, connecting the upper portion of the secondary heater with the pipe D, the said pipes d f being provided with dampers e g, and a damper, a, for closing the pipe D above its connection with the pipe f, substantially as set forth.

In testimony whereof I affix my signature in presence of two witnesses.

HEINRICH P. HEITMANN.
